ELECTRICAL OUTLET PLUG

Edward G. Schaeffer, Holyoke, Mass.

Application April 9, 1941, Serial No. 387,603

3 Claims. (Cl. 173—361)

This invention has to do with electric outlet plugs of the type which include a body of insulation material and a pair of contact prongs of conducting material to which the terminals of the conductor wires are connected and the invention is directed to an improved construction of plug and method of producing the same.

The invention primarily comprehends an improved method of producing an outlet plug of the character set forth by means of which the assembly of the contact prongs with the plug body is facilitated and a secure and lasting connection therebetween is insured as long as the body remains intact.

The invention further resides in certain improvements in the structure of the contact prongs which render the connection between the same and the plug body more effective, together with improved means provided on the prongs for establishing connection of the conductor wires therewith.

The invention is further directed to an electric outlet plug consisting of a body of insulation material having an axially extending opening formed with an oblong mouth portion provided with oppositely arranged recesses spaced from the end of the mouth portion and a pair of contact prongs having lateral anchoring projections which are positioned at the opposite ends of the mouth portion and are provided with lateral anchoring projections disposed within the recesses and which are secured in place by a block of insulation material frictionally fitted within the mouth portion of the opening between the contact prongs.

With the above recited and other objects in view, the invention is set forth in greater detail in the following specification and illustrated in the accompanying drawing in which:

Fig. 1 is a longitudinal sectional view illustrating an electric outlet plug body being molded with the mold sections shown in associated relation during the molding operation.

Fig. 2 is a collective view showing the molded plug body removed from the mold with the mold sections in separated juxtaposition thereto.

Fig. 3 is a sectional view on the line 3—3 of Fig. 1.

Fig. 4 is a collective sectional view taken on the line 4—4 of Fig. 2.

Fig. 5 is a longitudinal sectional view of the finished outlet plug with the wiring attached to the contact prongs.

Fig. 6 is a longitudinal sectional view taken approximately on the line 6—6 of Fig. 5.

Fig. 7 is an end view of a plug.

Fig. 8 is a detail perspective view of one of the contact prongs.

Referring to the drawing by characters of reference, the plug body 40 which is composed of hardened plastic material, such as hard rubber, is provided with a recess 41 of cross sectional oblong shape extending axially inward from the forward end 42 of the plug body and providing parallel opposite side walls 43 respectively formed intermediate the ends with oppositely disposed grooves or depressions 44 in spaced adjacent relation to the forward end 42 of the plug body.

The recess 41 is also defined by parallel opposite end wall portions 45 extending inwardly from the forward end of the plug body terminating in the region of the grooves or depressions 44 and merging into forwardly diverging end wall portions 46 to provide at the juncture with the end wall portions 45 undercut clearance spaces 47. The plug body 40 is formed with an axially extending opening 48 extending inwardly from the rear end 49 thereof and communicating with the recess 41 to provide a bore for receiving therethrough the extension cord 50 housing the conductor wires 51.

The outlet plug further includes a pair of contact prongs 52 each of which is preferably cut, bent and formed from a flat strip of metal bent upon itself intermediate the ends to provide a double ply outer end portion 53 for engagement within an electric outlet socket. The single ply inner end portion 54 of each contact prong which is adapted to be arranged within the recess 41 of the plug body, is provided intermediate its ends with lateral projections 55 spaced from the double ply portion an appropriate distance to register with the grooves or depressions 44 when the contact prongs are assembled with the plug body. The inner end portions 54 are each provided further with a reversely bent terminal 56 defining a bendable terminal clip for clamping engagement with the conductor wires 51 for attaching the same thereto.

In assembling the contact prongs with the plug body, the inner end portions are inserted in the recess 41 with the projections 55 extending lengthwise of the recess or parallel to the side walls 43 until the projections 55 align with the grooves or depressions 44. The prongs are then turned in a direction so that the reversely directed terminals 56 are disposed towards the end walls 45 with the projections 55 engaging in the oppositely disposed grooves or depressions 44 and the inner end portions 54 are brought into flat contact with the end wall portions 45 while the terminal clips with the conductor wires 51 se-

cured thereto are disposed within the undercut clearance spaces 47, it being understood that one contact prong is disposed adjacent one end wall portion and the other adjacent the other end wall portion. A block 57 of insulation material of a width to snugly fit and frictionally engage the side walls 43 and of a length to clamp the prongs in flat contact respectively with the opposite end wall portions 48 is then forcibly wedged into the recess with its outer end surface flush with the forward end 42 of the plug body. This effectually secures the prongs in assembled relation with the plug body with the outer end portions 53 projecting outwardly therefrom. This also spaces the uninsulated terminals of the conductor wires 51 and provides effective insulation between the contact prongs throughout the entire length of the inner end portions 54. In event that it is desired to detach the plug from the conductor wires, an instrument may be inserted through the opening or bore 48 to force the block 57 outwardly and thereby permit of the disassembly of the contact prongs from the plug body.

In producing an electric outlet plug of the type illustrated, the following method is employed: A two part mold is used including a mold body A having a mold cavity B which conforms to the exterior configuration of the plug 40. A mold cap C is adapted to be arranged over the open side of the mold and is provided with a core D adapted to be emplaced in the mold cavity B to form the recess 41 and opening or bore 48. The core D is provided with offset depression or groove forming portions E at opposite sides thereof and oppositely projecting portions F for forming the undercut clearance spaces. The method consists in initially molding the plug body 40 in the mold cavity B and about the core D as illustrated in Figs. 1 and 3 of the drawing, the molding operation being carried out so as to leave the insulation material of which the body is formed in a yieldable resilient state. The mold body A and the mold cap C are then separated and the molded plug body 40 while in the yieldable resilient state, is stripped from the core D, it being understood that the yieldable resilient state permits of the flexing or yielding of the body to permit the projecting portions E and F to be separated. The plug body is then treated to harden the same, such as by heating, to produce vulcanization thereof. The contact prongs 52 are then inserted in the recess 41 in the manner previously specified and the insulation block 57 is frictionally fitted into the recess between said pair of prongs for securing the inner end portions of the prongs within the plug body with the outer end portions protruding therethrough.

What is claimed is:

1. In an electric outlet plug, a body of insulation material having a recess of cross sectional oblong shape extending axially inward from the forward end of the plug body, opposite side walls

5 of the recess having depressions extending longitudinally of said side walls to the end walls thereof and spaced from the mouth of the recess, a pair of contact prongs each having a pair of lateral projections adjacent the inner end thereof to provide an inner end portion of greater width than the width of the mouth of said recess, said prongs having their inner end portions disposed in said recess in engagement with the opposite 10 end walls thereof respectively with the projections extending into said depressions, and a block of insulation material fitted within the recess between said pair of prongs and functioning to clamp the prongs in flat contact respectively with the opposite end walls of the recess.

2. In an electric outlet plug, a body of insulation material having a recess of cross sectional oblong shape extending axially inward from the forward end of the plug body, opposite side walls of the recess having depressions extending longitudinally of said side walls to the end walls thereof and spaced from the mouth of the recess, a pair of contact prongs each having a pair of lateral projections adjacent the inner end thereof to provide an inner end portion of greater width than the width of the mouth of said recess, said prongs having their inner end portions disposed in said recess in engagement with the opposite end walls thereof respectively with the projections extending into said depressions, bendable terminal clips formed integral with the inner extremities of the contact prongs for clamping conductor wires thereto, said recess having an outwardly flared portion at each end thereof providing undercut clearance spaces for accommodating the terminal clips and permitting the prongs to flatly contact with the end walls of the recess adjacent the forward end of the plug body, and a block of insulation material fitted within the recess between said pair of prongs and functioning to clamp the prongs in flat contact respectively with the opposite end walls of the recess.

3. In an electric outlet pair, a body of insulation material having a recess extending inwardly from the forward end of the plug body, opposite portions of the wall of the recess having depressions extending along opposite sides of the recess to the ends thereof and spaced from the mouth of the recess, a pair of contact prongs each having a pair of lateral projections adjacent the inner end thereof to provide an inner end portion of greater width than the width of the mouth of said recess, said prongs having their inner end portions disposed in said recess in engagement with opposite walls thereof respectively and with the projections extending into said depressions, and a block of insulation material fitted within the recess between said pair of prongs and functioning to clamp the prongs against said opposite walls of the recess.

EDWARD G. SCHAEFFER.
